UNITED STATES PATENT OFFICE.

WILLIAM C. ANDERSON, OF TOLEDO, OHIO, ASSIGNOR TO THE LIBBEY
GLASS COMPANY, OF SAME PLACE.

DESIGN FOR A GLASS DISH.

SPECIFICATION forming part of Design No. 24,356, dated June 4, 1895.

Application filed March 26, 1895. Serial No. 543,283. Term of patent 7 years.

To all whom it may concern:

Be it known that I, WILLIAM C. ANDERSON, a citizen of the United States of America, residing in Toledo, county of Lucas, and State of Ohio, have invented and produced a new and original Design for a Glass Dish, of which the following is a specification.

The design consists in the ornamentation of glass dishes having a semi-ellipsoidal form.

10 The design, as particularly shown, is applied upon a dish of the above general form, but having the lateral sides inwardly curled.

15 In the accompanying drawings, Figure 1 is a bottom plan view of the dish embodying the construction and embellishment of the design. Fig. 2 is a cross-sectional view, and Fig. 3 is a side elevation.

20 The prevailing feature of this design consists in an eight-tongued star rosette, A, at the center of the bottom of the dish, with the four diagonally projecting outlying shield-formed figures, B, B, extending from the opposite ends of the rosette to near the edge of the dish, which is scalloped, the angular bases of 25 which shield-formed figures, B, lie within or conform to the re-entrant boundaries of the rosette, together with the star-shaped figure which is much larger than, and widely inclose the rosette, the points of which star-

shaped figures are indicated by C, whereby 30 there are produced, in conjunction with the figures, B, the marginal fan-shaped or outwardly divergent figures, D. The rosette is embellished by groovings or cuttings to constitute a faceted round center piece, surrounding 35 triangular, pyramidal, projections, and the cross-hatched star-points.

The shield-formed figures, B, and the star-points, C, are sub-divided and have linear grooving or cutting to constitute a stellated 40 effect and the production of truncated pyramidal projections, while the fan-like marginal figures, D, D, are cut in representation of outwardly divergent ensiform leaves, whereby a suggestion of Egyptian ornamentation 45 is derived.

The inwardly curled lateral portions of the dish are indicated by x, and appear more prominently in Fig. 2.

What I claim is—

50 The design for the ornamentation of a glass dish, substantially as herein shown and described.

WILLIAM C. ANDERSON.
